UNITED STATES PATENT OFFICE.

EDWIN J. WALKER, JR., OF PENN YAN, NEW YORK.

DESIGN FOR A FIXTURE FOR STORES.

49,499.

Specification for Design.

Patented Aug. 8, 1916.

Application filed April 4, 1916. Serial No. 88,946. Term of patent 14 years.

To all whom it may concern:

Be it known that I, EDWIN J. WALKER, Jr., a citizen of the United States, and a resident of the village of Penn Yan, county of Yates, State of New York, have invented a new, original, and ornamental Design for Fixtures for Stores, which is shown in the accompanying drawing, in which the figure is a perspective view of a fixture for stores, embodying the design.

I claim:

The ornamental design for a fixture for stores, substantially as shown.

EDWIN J. WALKER, JR.

Witnesses:

W. M. PATTERSON,
C. H. FEIRNBAUGH.
